CLAIM

I claim the ornamental design for a vault, as shown and described.

DESCRIPTION

FIG. 1 is a top, front, right perspective view of a vault in a closed configuration showing the new design.

FIG. 2 is a front elevation view of the vault.

FIG. 3 is a rear elevation view of the vault.

FIG. 4 is a left side elevation view of the vault.

FIG. 5 is a right side elevation view of the vault.

FIG. 6 is a top plan view of the vault.

FIG. 7 is a bottom plan view of the vault; and,

FIG. 8 is a perspective view of the vault in an open configuration.
